UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

DESIGN FOR A LATCH-BOLT.

SPECIFICATION forming part of Design No. 29,384, dated September 20, 1898.

Application filed August 24, 1898. Serial No. 689,438. Term of patent 7 years.

To all whom it may concern:

Be it known that I, WARREN H. TAYLOR, a citizen of the United States, and a resident of Stamford, in the county of Fairfield and State 5 of Connecticut, have invented and produced a new and original Design for a Latch-Bolt, of which the following is a specification, reference being had to the accompanying drawings, forming part thereof.

10 Figure I is a perspective view showing my new design for a latch-bolt. Fig. II is a top view thereof. Fig. III is a side view of the same.

15 As shown in the drawings, the leading or material features of my design consist of a flat tail having a twist at the head or outer end and bifurcated at the inner end to provide extremities which extend at right angles

to the tail rearwardly and forwardly, or vice versa, respectively.

20 The latch-bolt has a head from which extends a flat tail twisted at the portion contiguous to the head. The inner end of the tail is bifurcated and the extremities project in opposite directions from the rear and front, 25 or vice versa, respectively.

Having thus described my invention, the following is what I claim as new therein and desire to secure by Letters Patent:

25 The design for a latch-bolt, substantially 30 as herein shown and described.

WARREN H. TAYLOR.
